PISTOL

William B. Ruger, Westport, Conn., assignor to Sturm, Ruger & Co., Inc., Southport, Conn., a corporation of Connecticut

Application April 29, 1950, Serial No. 9,594

Term of patent 14 years

(Cl. D30—1)

To all whom it may concern:

Be it known that I, William B. Ruger, a citizen of the United States, residing at Westport, Fairfield County, Connecticut, have invented a new, original, and ornamental Design for a Pistol, of which the following is a specification, reference being had to the accompanying drawing forming a part thereof.

Fig. 1 is a side view of a pistol showing my new design;

Fig. 2 is a bottom view of the pistol showing the grip portion; and

Fig. 3 is a rear elevation.

The dominant features of my design reside in those portions shown by means of full lines in the drawing.

I claim:

The ornamental design for a pistol, as shown and described.

WILLIAM B. RUGER.
